PILOT STEM

Clarence T. Rottler, Seattle, Wash.

Application November 22, 1938, Serial No. 241,764

14 Claims. (Cl. 90—12.5)

The present invention relates to pilot stems for insertion in bores to serve as an axial guide means for an operation to be performed upon the bore or upon some surface which is, or which 5 is intended to be, coaxial with the bore. Such a device finds a particular application in the reseating of the valve seat of an internal combustion engine, the pilot stem being brought into substantial axial coincidence with the axis of 10 the bore which normally receives and guides the valve stem, and then serving as a means to position or axially align a reseating or grinding tool relative to the valve seat.

Such pilot stems generically are old, but it has 15 been found difficult heretofore to secure exact axial coincidence between the pilot stem and the bore, and if occasionally exact axial coincidence is obtained it is largely fortuitous. The difficulty in insuring axial coincidence, with certain 20 former constructions, is that it has been attempted to secure this by centering a rod at one point of engagement with the bore, hoping thereby to obtain substantial coincidence between the axis of the rod and of the bore. However, because the 25 tight engagement of the rod within the bore is at one point only, usually at the entrance to the bore through the medium of a taper on the rod inserted within the entrance, this does not obtain axial coincidence, but merely centering of this 30 particular circle of engagement; if there is any looseness between the rod and the bore at other points in the length of the rod, as there must be in practice in order to permit insertion of the rod through the bore, this looseness, though minute 35 amount, causes some tilt of the axis of the rod relative to the axis of the bore, and the entire valve grinding or reseating operation becomes inaccurate. While the actual deviation may be slight—and the measurements with which we are 40 dealing are of the order of thousandths or tens of thousandths of an inch—nevertheless even a minute deviation from true axial coincidence, when magnified by the greater diameter of the valve seat, becomes of considerable practical importance.

Attempts have been made to remedy this difficulty by centering the inserted end of the rod, relative to the inner or distant end of the bore, by means operable independently of the taper 45 at the entrance to the bore, for instance, by expansive devices at the distant end of the bore, but this has not proven entirely satisfactory, and in particular is in certain constructions attended with the difficulty of having to reach inside the 50 engine to the lower end of the bore, and there

in a restricted space to adjust a centering means.

In other prior devices it has been attempted, by adjusting means extending through an axial bore in the stem to avoid the necessity of adjusting a lower centering device from within the 5 engine, or at the lower end of the bore. Since the bore is of small diameter and the stem must be even smaller, a hole through the stem's axis weakens the stem, and withal the adjusting device is still so small and frail that it can not be 10 relied upon to accomplish the adjustment properly or accurately, nor to stand up under rough treatment which it is bound to receive when used by careless mechanics, men not thoroughly skilled in the use of such tools. Such devices are therefore 15 unsuitable, largely because of the necessarily small size of the operating parts, or the weakening of the stem itself if the operating parts are made larger.

To provide a larger operating element to control the adjustment of a sleeve threaded on the inserted end of a rod, without weakening the rod, it has been attempted to adjust the sleeve with relation to an expanding taper on the rod, by rotating the rod itself, the sleeve being held 20 against rotation by frictional engagement with the wall of the bore. This will unquestionably 25 effect expansion of the sleeve, and if the sleeve expands fully, and remains concentric with the rod, the latter will unquestionably be correctly 30 centered at this distant end, and aligned throughout its length, but still such devices have been 35 found impractical in use. The mechanic only knows that he must rotate the projecting end of the stem to expand and tighten the sleeve, and does not realize that he can expand the sleeve too greatly, even before its frictional grip is sufficient to prevent further rotation of the rod. He turns the rod, and continues to turn it, perhaps believing that the sleeve is slipping or 40 rotating within the bore, and knowing that the top taper is resisting rotation of the rod, and so greatly expands the sleeve that it breaks, or 45 expands it to a point where it will not again contract to its original diameter or shape—it becomes permanently deformed and is not longer accurate. He continues to turn the rod until the sleeve does finally grip and refuse to turn farther, and then he tries to turn the rod a little 50 farther to insure that it is tight. In thus turning the rod against resistance (whether of the top taper or of the expanded sleeve) he strains it, and bends or breaks it. The difficulty is that he has no way of telling when the stem as a whole 55 is centered, and there is nothing to prevent turn-

ing the rod too far. Force must be exerted on the rod to tighten the expanding sleeve, and since insufficient force leaves the sleeve loose, excessive force will usually be employed, and such 5 force injures the stem and destroys its accuracy.

On the other hand, the top taper is so slight that it wedges easily, and resists rotation of the rod, before the rod has turned sufficiently to expand the sleeve to the desired degree. By this 10 wedging of the top taper, as it rotates, the rod may be engaged tightly enough that it will not turn farther, tightly enough that the engine block may be lifted by the wedged rod—yet, if it becomes so wedged after one turn, and three turns 15 are necessary to effect sufficient expansion of the sleeve on the lower taper, it is self-evident that the sleeve is loose within the bore by a lack of expansion equivalent to two turns. If the sleeve is left thus loose—and if the rod can not be turned farther the average mechanic is justified 20 in believing that the sleeve must be tight—it can not perfectly center the rod, and lack of axial coincidence results. It is essential, if the rod must be rotated, that the sleeve's expansion 25 be not dependent, in degree, upon the amount of rotation of the rod, but that the sleeve's expansion be fully accomplished by means which operate independently of the rod's rotation, though such means may be tripped or set in operation 30 by rotation of the rod.

It is the principal object of this invention to provide a pilot stem for such uses, which is so constructed as to automatically secure substantially exact axial coincidence between the axis 35 of the rod and the axis of the bore by reason of two automatic centering devices in the nature of tapers acting upon two circles or zones, spaced well apart toward opposite ends of the bore, to the end of reducing the possibility of lack of coincidence to the minimum, and as a subsidiary object it is a further object to effect this coincidence by means which are operable wholly exteriorly 40 of the bore, and from the projecting end of the rod, and exerting automatically a force sufficient to effect proper centering, but unlikely to have applied to it any excessive force, since the centering of the lower end is automatic, and the user 45 knows when the latter occurs, and needs only to center the upper taper.

A further difficulty with former devices has 50 been that the centering of a particular portion of the rod (the distant or inner end, usually) has been effected almost solely by line contact about a circle, such as the contact of a taper with the edge constituting one or the other end of the bore, and since such edge or line contact may 55 be rendered inaccurate by inaccuracy of the edge itself, or by slight unnoticeable deformation of one or the other of the contacting surfaces or edges, it is a further object to effect this axial coincidence, in part at least, by engagement throughout a zone of appreciable length of the bore, thus to avoid inaccuracy due to line contact.

It has also been proposed to effect centering, 60 usually at the inserted end of the rod, by an expandable sleeve slit throughout its length, and expanded by screwing it along the rod against an expanding taper. While this sleeve may be coaxial with the rod when collapsed, when expanded by separation of the edges of the slit it loses, even though by a small amount, true axial coincidence, which throws the rod off, and it is no longer truly cylindrical, hence bears along a line or lines instead of over a cylindrical surface, 65 thereby increasing the possibility of failure to

retain axial coincidence, statically or under stress. A further object of this invention is to provide a structure which will eliminate these possibilities of error.

It is a further object to provide a pilot stem 5 of the character indicated, automatically and simply self-centering, under control of the user, when inserted, which is simple and rugged in construction, made of few parts, operable with a minimum of effort, and capable, in all parts 10 where this is necessary, of precision manufacture, all to the ultimate end that there shall be provided a pilot stem which with unfailing accuracy will at all times align itself axially with the axis 15 of the bore, and will provide an unfailingly accurate guide for further operations, such as the grinding or reseating of a valve seat.

To the above ends my invention comprises the novel pilot stem as a whole, and the novel combination and arrangement of the elements thereof, as shown in the accompanying drawing, described in this specification, and as will be more particularly defined by the claims which terminate the same.

In the accompanying drawing I have shown 25 my invention embodied in a form which is at present preferred by me, it being understood, however, that the principles of this invention, in accordance with the appended claims, may be incorporated in other forms and arrangements, 30 and this specification, while directed to a specific form, is to be understood as explanatory rather than as restrictive.

Figure 1 is a general elevation of the pilot stem and an associated valve seating tool, shown in 35 operative position, the bore, valve seat, and associated parts being shown in section.

Figure 2 is an enlarged elevation of the stem, with parts in section, and in the positions they occupy in Figure 1.

Figure 3 is a further enlargement of the inner 40 or inserted end of the stem, showing parts in the position they would occupy during insertion.

Figure 4 is a top plan view of the sleeve which forms part of the stem, and which constitutes its 45 inner centering and bearing member.

The particular type of tool with which the stem cooperates is per se immaterial, but in order to afford an understanding of the stem and of the reason why it must be so accurately located, a valve seating tool of the type which is disclosed 50 in detail in my copending application Serial No. 211,181, filed June 1, 1938, is shown in Figure 1, in association with the stem. This valve seating tool comprises a body 9 having a conical surface 55 90 which is shaped to seat upon a perfectly shaped valve seat 80, in an engine block 8, the tool being provided with a cutting bit 91 which is intended to be projected from the conical surface 90 to a minute extent (the adjustment being regulated 60 by a threadedly mounted adjusting element 92), so that as the tool is rotated, axially aligned with the axis of the seat 80, it will in effect seat throughout its entire periphery by engagement 65 of the conical surface 90 with the conical seat 65 80, and the tool 91 will project only to an extent to remove the high surfaces or points of the valve seat, but insufficiently to raise the conical surfaces 90 and 80 from substantially full contact with each other. This tool is guided largely 70 by the contact of the two conical surfaces mentioned, yet still it must be centered relative to the axis of the valve seat, and this centering is accomplished by a rod 1, which forms part of the pilot stem, this rod having a portion which pro- 75

jects upwardly above the valve seat 80 for the reception of the valve seating tool.

If the axis of the rod 1 be not in substantially precise coincidence with the axis of the valve seat 80, but if it be instead tilted slightly, to the left, for instance, as seen in Figure 1, then by reason of the enlarged diameter of the valve seat, the tool 91 will cut more deeply at the left in Figure 1, and more lightly at the right, with the result that the valve seat becomes tilted with respect to the surface 81, and therefore somewhat elliptical, and the valve, when replaced, does not seat accurately. Moreover, more work is required since more material must be removed to make the seat elliptical, and the final result is that the valve does not seat accurately and the engine does not function efficiently. Other disadvantages arise from such an imperfectly aligned rod, but enough has been said to indicate why precise alignment must be obtained if possible.

It may be assumed that the bore 82, within which the stem of the valve is received, is accurately and precisely aligned with the axis of the valve seat 80, for originally the valve seat was so located by reference to the bore. The axis of this bore 82 may therefore be taken as the reference line from which all other determinations are made, but it is useless as a reference line unless the axis of the stem 1 may unfailingly be brought into precise axial coincidence with the axis of the bore, and it is at this point that prior devices have failed.

The stem 1 may be caused to seat at the entrance to the bore 82, which would normally be its upper end, and to center itself in the circle which defines this entrance by providing a taper 11, intermediate the ends of the rod 1, which is of a size and shape to seat in the entrance to the bore. This, however, only centers the circle of contact between the taper 11 and the entrance to the bore, and does not, of itself, insure axial coincidence between the bore and the rod. Since axial coincidence can best be assured by two accurate bearings, spaced as far apart as is feasible, I provide self-centering means which will engage the distant, usually the lower, end of the bore 82, and which will center this end of the rod, and thereby, by cooperation with the centering afforded by the taper 11, will effect substantial axial coincidence between the rod and the bore.

The means to the latter end may vary somewhat. In effect they are constituted by a plurality of radially and equally movable wedging or gripping elements, together with means, preferably operable from the projecting or upper end of the rod, and under the limited yet sufficient force of a spring, to effect their radial expansion; preferably also in much the same way their retraction is effected, though, of course, in opposition to the spring.

Thus, adjacent the inner or inserted end of the rod 1 I provide a second taper 12, which should taper in the same direction as the taper 11. The two need not be parallel, but tend toward parallelism, both being inclined in the same direction relative to the axis of the rod. In this connection, and generally in connection with the description of this pilot stem, it must be borne in mind that the dimensions, clearances, and proportions as shown in the drawing must be exaggerated for purposes of illustration, and that in practice the tapers, certainly the taper 11, may be so minute as to be barely perceptible. Such

tapers may be very accurately finished by grinding.

Cooperating with the second taper 12 are the wedging elements, and for convenience these elements are formed as part of a sleeve 2, which is 5 slidable lengthwise upon a reduced portion 13 of the rod, beyond the taper 12 from the taper 11. This sleeve is slit lengthwise at spaced points from its top downwardly for a part of its length, but preferably the slits 20 do not extend the entire length of the sleeve, leaving an unslit portion at its lower end, which is closely guided upon the reduced portion 13 of the rod. This leaves longitudinally extending fingers 21, which are somewhat resilient so that they may be moved outwardly when the sleeve as a whole is moved lengthwise of the rod into engagement or into more firm engagement with the taper 12. The inside of the fingers 21 may be complementally tapered to engage the taper 12, if desired, and 10 preferably in the vicinity of their taper-engaging portion they are exteriorly formed cylindrically, as indicated at 22, to effect a bearing or gripping engagement throughout an appreciable portion 15 of the length of the bore 82, thus to avoid mere 20 line contact with the wall of the bore.

Normally, that is, for insertion of the stem, the fingers 21 and their gripping portions 22 are retained in a position where they are collapsed, that is, where they are expanded radially outward to 25 the least degree, yet still they should be of sufficient diametrical extent that they frictionally engage the wall of the bore 82. It is further desirable, after the stem is inserted and the first 30 taper 11 is well seated in the entrance to the bore, that the wedging elements 21, 22 should be radially and equally expanded in all directions, and by a predetermined force which tends to pull the rod 1 further into the bore 82, thus to 35 seat the taper 11 more securely in the entrance 40 to the bore.

The latter ends are secured, in the construction shown, by providing a head 3, which is riveted or otherwise permanently secured on the end of the rod, by providing an expansion spring 4 reacting between the head 3 and the lower end of the sleeve 2, and by restraining the sleeve against the action of the spring 4 by a retaining means shown as formed of a pin 14 projecting laterally from the rod and received within an angled slot 50 in the sleeve 2, and indicated generally at 24. When the pin 14 is received in that branch of the slot 24 which extends in a peripheral direction, the sleeve 2 is held drawn away from the taper 12, and the spring 4 is compressed. It is 55 not to be implied that the upper end of the sleeve must not touch the taper 12, even though so shown in Figure 3, but it must not press against the taper 12 sufficiently to expand the upper ends of the fingers 21 into gripping engagement with 60 the wall of the bore. However, when, by rotation of the rod 1 relative to the sleeve 2, the pin 14 has been brought into registry with that branch of the slot 24 which extends lengthwise of the sleeve, the sleeve, under the impulse of the compressed spring 4, is moved or thrust upwardly, and by reaction the rod 1 is pulled downwardly or inwardly, and now, as the free ends of the fingers 21 ride up on or engage more firmly with the taper 12, the fingers are moved or pressed radially 65 outwardly, increasing the frictional grip of the cylindrical outer surfaces of the gripping portion 22 upon the wall of the bore, and wedging between the taper 12 and the wall of the bore, to effect centering of this lower or inserted end of 70 75

the rod, the unslit portion of the sleeve being always coaxial with the rod. At the same time, the rod being drawn downwardly, the taper 11 is moved the more firmly into engagement with the entrance to the bore, and if its cross-sectional circular plane of contact had been tilted relative to the bore's entrance, it is returned to planar coincidence. The result is that each of these points of engagement between the rod and the bore is automatically self-centered with the bore at this particular point or zone, and since there is coincidence of the rod's axis at each of two rather widely spaced points, it follows that there must result substantially exact axial coincidence between the rod 1 and the bore 82.

It has been stated above that the sleeve, at least its portion 22, when in the position of parts shown in Figure 3, frictionally engages the wall of the bore 82. This need not be too close frictional engagement, but must be sufficient that when the upper or projecting end of the rod is rotated (as, for instance, by a cross pin received in the transverse hole 15), the sleeve 2 will not rotate, thereby permitting the pin 14 to move into registry with the lengthwise branch of the angled slot 24, and as soon as these are brought into registry, lengthwise movement of the sleeve 2 relative to the rod 1 is accomplished, under the influence of the spring 4, thereby tremendously increasing the frictional grip of the elements 22. Thus the stem as a whole may be inserted into the upper or near end of the bore 82, until its taper 11 is seated at the entrance to the bore, and then by rotation of the projecting end of the rod the sleeve is brought into wedging or gripping engagement with the distant or inner end of the bore, in the manner just described. When it is desired to remove the pilot stem it is only necessary to pull upwardly on the rod 1, again compressing the spring 4, rotating the rod 1 in the opposite direction to move the pin 14 into the peripherally directed branch of the slot 24, whereupon, with the fingers 21, 22 again retracted by their natural resilience, the stem as a whole may be lifted out of the bore.

What I claim as my invention is:

1. A pilot stem for reception in a guide bore, comprising a rod formed intermediate its ends to seat on and to center itself relative to the near end of the bore, a normally collapsed but resiliently expandable sleeve which in all positions is coaxial with and guided upon the distant end of the rod for movement relative to the rod, means to retain said sleeve in a position wherein it is collapsed, the sleeve when thus collapsed being of a size to frictionally engage the walls of the bore, means operable by movement of the rod relative to the frictionally engaged sleeve, when each is thus engaged, within the bore, to release said retaining means, and means operable as a result of such release to effect expansion of the sleeve into gripping and self-centering engagement with the bore, thereby centering the distant end of the rod with the bore, and aligning the rod as a whole coaxially with the bore.

2. A pilot stem for reception in a guide bore, comprising a rod formed intermediate its ends to seat on and to center itself relative to the near end of the bore, an expandable sleeve which in all positions is coaxial with and guided upon the distant or inserted end of the rod for movement axially along the rod, means operable by movement of the sleeve towards the rod's seating portion to expand the sleeve radially into gripping engagement with the wall of the bore, there-

by, in cooperation with the seating portion, to effect substantial coincidence between the axes of the rod and bore, means active to effect such movement of the sleeve, and means, releasable from the projecting end of the rod to permit such movement, operable to restrain the sleeve against such movement during insertion of the rod.

3. A pilot stem for reception in a guide bore, comprising a rod formed intermediate its ends to seat on and to center itself relative to the near end of the bore, an expandable sleeve which in all positions is coaxial with and guided upon the distant or inserted end of the rod for movement axially along the rod, means operable by movement of the sleeve towards the rod's seating portions to expand the sleeve radially into gripping engagement with the wall of the bore, thereby, in cooperation with the seating portion, to effect substantial coincidence between the axes of the rod and bore, means active to effect such movement of the sleeve, and means, releasable by rotary movement in one direction of the projecting end of the rod relative to the sleeve to permit such movement, operable to restrain the sleeve against such movement during insertion of the rod, and reengage by rotary movement in the opposite direction of the rod relative to the sleeve, to enable collapse of the sleeve during withdrawal of the rod.

4. A pilot stem for reception in a guide bore, comprising a rod tapered intermediate its ends to seat on and to center itself relative to the near end of the bore, a normally collapsed but resiliently expandable sleeve in all positions coaxial with and guided upon the distant end of the rod for movement lengthwise of the rod, means to retain said sleeve in a position wherein it is collapsed, the sleeve when thus collapsed being of a size to frictionally engage the walls of the bore, and means operable by limited movement of the rod relative to the frictionally-engaged sleeve, when each is thus engaged within the bore, to release said retaining means and to effect immediate expansion of the sleeve into gripping and self-centering engagement with the bore, and coincident movement of the sleeve lengthwise of the rod and towards its taper, thereby centering the two ends of the rod with the bore, and locating the rod as a whole coaxially with the bore.

5. A pilot stem for reception in a guide bore, comprising a rod tapered intermediate its ends to seat on and to center itself relative to the near end of the bore, a sleeve having a non-expandable portion closely embracing the distant inserted end of the rod to guide the sleeve for movement lengthwise of the rod, and having a resilient radially expandable portion of a size and shape, when not expanded, to frictionally engage the inner wall of the bore, means to urge the sleeve along the rod in a direction towards the rod's taper, the rod and sleeve having complementary means operable by movement of the sleeve towards the rod's taper to expand the sleeve into gripping engagement with the wall of the bore, and the sleeve being externally shaped to engage, when expanded, an appreciable portion of the length of the bore, thereby to center the sleeve and the corresponding end of the rod within the bore, and to draw the taper firmly into the entrance to the bore, thereby, in conjunction with the aforesaid centering action, to effect substantial coincidence between the axes of the bore and rod, and means, releasable from the projecting end of the rod, to retain the sleeve in a position wherein it is collapsed.

6. A pilot stem for reception in a guide bore, comprising a rod having a first taper intermediate its ends, of a size and shape to seat on the entrance to the bore, and to center itself and the intermediate part of the rod relative to such entrance, the rod also having a second taper, in the same direction, adjacent its distant or inserted end, wedging elements distributed about the rod's inserted end inwardly of the second 10 taper, and engageable with the second taper, when moved towards the same, to be thereby expanded radially and equally into gripping engagement with the bore's wall, to center this inserted end of the rod with the bore, and hence, 15 in cooperation with the first taper, to effect substantial coincidence between the axes of the rod and bore, means urging said wedging elements towards wedging position; and means acting in opposition to the latter means, and releasable 20 from the projecting end of the rod, to retain said wedging elements in non-wedging position, thereby to withhold them from such radial expansion during insertion of the rod.

7. A pilot stem for insertion within a guide bore, comprising a rod having a first taper intermediate its ends, of a size and shape to seat on the entrance to the bore, and to center itself and the intermediate part of the rod relative to such entrance, a head formed on the rod at its distant or inserted end, the rod also having a second taper, in the same direction as the first, adjacent the head but between the head and the first taper, wedging elements distributed about the rod, between the head and the second taper, 30 and engageable with the second taper, when moved towards the same, to be thereby moved radially and equally into wedging engagement between the second taper and the bore's wall, to center this inserted end of the rod within the bore, and hence, in cooperation with the first taper, to effect substantial coincidence between the axes of the rod and bore, means releasable from the projecting end of the rod to retain said wedging elements withdrawn towards the head, 40 thereby to withhold them from such engagement with the second taper during insertion of the rod, and spring means reacting, lengthwise of the rod, between the head and the wedging elements, whereby upon release of said retaining means, 45 to simultaneously urge the first taper into the entrance to the bore, and to thrust the wedging elements towards the bore's entrance into operative engagement with the second taper.

8. A pilot stem as in claim 7, including a sleeve coaxial with and slidable lengthwise of the inserted end of the rod, and having lengthwise slits spaced about its periphery, for a part only of its length, to constitute the wedging elements, the spring means reacting between the head and the unslit portion of said sleeve.

9. A pilot stem as in claim 7, including a sleeve coaxial with and slidable lengthwise of the inserted end of the rod, and having lengthwise slits spaced about its periphery, for a part only of its length, to constitute the wedging elements, the spring means reacting between the head and the unslit portion of said sleeve, and the retaining means comprising a pin projecting laterally of the rod and an angled slot in the sleeve, one branch whereof extends in a peripheral direction to retain the sleeve withdrawn against the action of the spring means, and the other branch whereof extends lengthwise of the sleeve, to permit movement lengthwise of the sleeve under the urging of the spring means when, by rotation

of the rod relative to the sleeve, the pin comes into registry with said lengthwise branch of the slot.

10. The combination of claim 6, wherein the wedging elements are formed by slitting a sleeve inwardly from one end only, at angularly spaced points, and for a portion only of its length, to define a plurality of substantially identical wall-engaging fingers resiliently supported from an integral unslit skirt, and wherein the retaining means is in part formed as part of said skirt, and in part upon the rod.

11. A pilot stem for insertion within a guide bore, comprising a solid rod of a transverse sectional area approaching the transverse area of such guide bore, an expandable sleeve encircling the insertible end of said rod, means permanently securing together said rod and said sleeve and restraining them from substantial relative rotative movement, and means operable by relative axial, non-rotative movement of said rod and sleeve in one direction to effect expansion of said sleeve into firm gripping engagement with the wall of the guide bore, and releasable by relative axial, nonrotative movement in the opposite direction for contraction of said sleeve.

12. A pilot stem for insertion within a guide bore, comprising a solid rod of a transverse sectional area approaching the transverse area of such guide bore, an expandable sleeve encircling the insertible end of said rod, means permanently securing together said rod and said sleeve and restraining them from substantial relative rotative movement, means operable by relative axial, non-rotative movement of said rod and sleeve in one direction to effect expansion of said sleeve into firm gripping engagement with the wall of the guide bore, and releasable by relative axial, non-rotative movement in the opposite direction for contraction of said sleeve, and means co- 35 operable with said first means by slight relative rotation of said rod and said sleeve to restrain such rod and sleeve from appreciable relative axial movement, thereby to lock said second 40 means against sleeve-expanding movement. 45

13. A pilot stem for insertion within a guide bore, comprising a rod having means intermediate its ends to center such intermediate portion within the entrance to the bore, an expandable annulus carried by the inserted end of said rod 50 and provided with a wedging surface, cooperating wedging means movable with respect to the wedging surface of said annulus to expand it into gripping engagement with the wall of the guide bore, spring means acting to urge said 55 wedging means and wedging surface into engagement to effect gripping expansion of said annulus, and spring control means operable to render said spring means inactive and incapable of effecting annulus expansion, and releasable to 60 render said spring means again active to effect expansion of said annulus into gripping engagement with the wall of the guide bore.

14. A pilot stem for insertion within a guide bore, comprising a rod having means intermediate its ends to center such intermediate portion within the entrance to the bore, an expandable annulus carried by the inserted end of said rod for engagement with the wall of the guide bore, and provided with an annular wedging surface, 70 cooperating wedging means movable axially relative to said annular wedging surface, a compression spring expandable axially of said annular wedging surface to force it and said wedging means together to expand said annulus into grip- 75

ping engagement with the wall of the guide bore, and spring control means operable from the end of the rod projecting outwardly from said first means to compress said spring and to retain it compressed for releasing said annulus from such wall gripping engagement, and further operable

from such projecting end of the rod to release said spring for expansion to force said wedging means and wedging surface together for expanding said annulus into such wall gripping engagement.

CLARENCE T. ROTTIER.
